UNITED STATES PATENT OFFICE.

EARL D. RADER, OF BEDFORD TOWNSHIP, WESTCHESTER COUNTY, NEW YORK, AS
SIGNOR TO DEXTER FOLDER COMPANY, OF NEW YORK, N. Y., A CORPORATION OF
NEW YORK.

FOLDING MACHINE.

Application filed November 24, 1925. Serial No. 71,167.

This invention relates to folders for signatures of various kinds and sizes. The object of the invention is to provide a construction whereby there may be performed on the well-known "jobbing" folder all the operations and folds that now require the standard jobber as well as the standard catalogue folder.

For a number of years the art has provided a series of jobbing folders of various sizes employing feeding tapes and reciprocating folding knives and also a similar line of catalogue folders to handle the requirements of the trade. A jobbing folder may be generally identified as one that folds four successive right angle folds; whereas the catalogue folder is one in which a sheet of paper is first folded with two parallel folds thereafter followed by one or more right angle folds. The jobbing type of folder is utilized to produce signatures of varying numbers of pages with an upright binding edge along the longer dimension; whereas the catalogue folder is utilized to produce signatures of varying numbers of pages of like size in oblong shape where the binding edge is along the shorter dimension. A number of different sizes of jobbing folders are provided to meet the requirements of the trade, and the same number of corresponding catalogue folders are also provided. Most of the work of the binderies may be performed on the jobbing folders, and the line of catalogue folders is provided to do a small percentage of the requirements of the trade.

The catalogue folder of any given size is more expensive than its corresponding jobbing folder by from $\frac{1}{4}$ to $\frac{1}{3}$; each catalogue folder requires more floor space than its corresponding jobbing folder; and generally the construction and operation of the catalogue folder is such as to render its purchase and maintenance a source of expense to the trade, in most cases out of proportion to the work that is done thereon.

Notwithstanding the fact that only a small percentage of the work of folding is done on these catalogue folders, and notwithstanding the fact that they are more expensive in their original cost and upkeep than the jobbing folders, binderies have nevertheless been forced to maintain the same in order to meet the varied requirements of their customers, or to do the catalogue folding by hand.

One of the objects that is accomplished by the present invention is the entire elimination of the whole line of catalogue folders that has for so many years been on the market in association with their corresponding jobbing folders; and this object is attained by combining with the first knife fold mechanism of the jobbing folder of a loop fold mechanism which, when used in association with the first fold mechanism of the jobber, subjects the sheet to the two parallel folds that characterize the catalogue work. This loop folding mechanism is so associated with the first fold mechanism of the jobber that its use may be readily and quickly dispensed with whenever it is desired to do jobbing work and not catalogue work.

The suppression of the entire line of expensive catalogue folders results in striking economies that start in the factory where the folders are built and ends with the printed and folded matter delivered to the customer. All the pages and folds that heretofore required a jobbing folder and its corresponding catalogue folder are now secured by the addition to the standard jobbing folder of the mechanism in question, and all the economies that follow the obsoleting of a line of machines both from the manufacturing standpoint and from the standpoint of the printer and binder are secured.

On certain all-loop folders now on the market, it is possible to do both jobbing and catalogue work, but this is effected entirely by the use of a series of loop mechanisms. This necessarily has limited the size of sheets that can be handled by such a folder, and the speed with which the folding can be effected. The output of these machines is necessarily limited because of the fact that the feeding and folding of the sheet is effected only at the surface speed of the folding rollers associated with the several loopers; and it is not profitable on such machines to handle sheets larger than approximately 22" x 28".

As herein illustrated, the present invention is associated with the standard jobber employing the usual tapes and folding knives in association with folding rollers whereby a high speed of output is maintained, and consists in addition to such mechanism of a loop fold device associated with the first fold mechanism of the jobber and so arranged that it may be readily used, or its use dispensed

with by a simple adjustment, thus entirely obsoleting the whole line of catalogue folders.

While, for the purpose of adapting a jobbing folder to also perform the work of a catalogue folder, any desired construction of looper mechanism may be associated with the first-fold knife, I prefer to employ a particular and novel construction of looper mechanism which has decided advantages in this particular combination as well as in any other relation where a looper may be desired. In this particular aspect of the inventive idea, this looper mechanism is constructed so that the sheet will readily and easily enter the same without buckling—that is to say, without having waves or undulations formed therein—to the end that premature folding is prevented and the loop is formed accurately, rapidly and with the maximum of efficiency. Heretofore, in order to suppress the forming of waves or undulations in the sheet as it entered the looper mechanism, it has been customary to provide means for changing the spacing of the grid members of the looper, depending upon the particular weight, texture and characteristics of the paper stock being handled. The formation of the waves or undulations in the sheets as they enter the grid are effected by the friction of the forward portion of the sheet with the grid surfaces with which it contacts, also the static electricity generated under certain climatic conditions; and the larger the sheet the more intensified is the waving or undulations formed in the sheet, and the tendency toward premature folding.

With these particular conditions in mind, the improved looper mechanism, instead of having its grid members straight and parallel, has its lower grid members struck on a curve so that the sheet entering the looper mechanism at high speed will follow the configuration of said curved grid members instead of tending to fill up the space between the straight parallel grid members of the prior art. Indeed, it has been found that the upper members that are associated with the lower curved grid members may be removed and looping effected simply by the use of the lower curved grid members. While it is true, that the sheet would normally encounter more frictional surface with a curved grid member than with a straight one, the fact that the sheet will follow accurately and definitely the surface of the curved grid member more than compensates for this condition. It has been found that, after the advancing edge of the sheet has been introduced into the curved grid members and its path of movement established, a substantial extent of grid surface can be removed, thus eliminating the frictional effect which this would have exercised on the sheet; and in this aspect the invention resides in the pro-

gressive decreasing of the frictional surfaces of the grid against which the sheet engages after it enters the same.

A further object of the invention is to provide a grid construction made up of separable unit elements which can be assembled in any desired relation or number to meet the particular operating conditions or the particular function to be subserved by the looper. In other words, if it is found that, under any particular climatic or other conditions, premature folding is developing by reason of an excess of friction surface, it is possible by the present invention to bodily and readily remove a number of the grid members in order to eliminate the excess friction surface, so that the sheet can be fed into the looper without premature folding and with the minimum of friction surface under any condition that may arise; and, on the other hand, if it is found that the sheet is entering the looper mechanism too freely so that the front edge is being injured by impact against the stop, the friction surface of the looper can be readily increased by the addition of one or more grid members to compensate for this condition. In this aspect of the inventive idea, I provide individual grid elements that are adapted to be mounted and adjusted in any desired position on the supporting rods.

This individual construction of grid members simplifies the construction and assembly of looper mechanisms and involves striking economies both from the standpoint of the manufacturer and the user. From the manufacturer's standpoint it is only necessary to produce one standard size grid member, and from the users' standpoint any size looper mechanism may be readily built up in situ to meet any desired condition. Further, by the use of this unit construction, it is possible to use the same on any size of folder, it being unnecessary to manufacture different sizes of loopers for different widths of folding machines.

A further object of the invention is to provide a deflecting mechanism which is adapted to be moved into or out of operative relation dependent upon whether the looper mechanism is to be used or not. Such deflector mechanism, according to the present invention, is made up of a series of deflecting units that may be independently assembled and which, when assembled, are mounted in fixed relation with respect to the grid members. Further, said deflecting members may be moved to operative or inoperative position by a simple manual adjustment without disassembling or altering the construction or operation of any of the associated parts.

A further object of the invention is to associate the folding rollers between which the sheet is introduced by the first-fold knife in such a relation that the sheet will readily and

accurately enter the same without being retarded in its movement or displaced by undue pressure existing between the rollers or resistance in the grid. In this aspect of the invention, the rollers are adjusted with respect to each other with any desired spacing therebetween, dependent upon the thickness and weight of the stock being folded, the normal spacing between the rollers being somewhat less than the thickness of the paper passing therebetween. This adjustment of the rollers with the space therebetween prevents marring of the stock, and also insures the ready and efficient folding of the same. The rollers are yieldingly supported in the desired position of adjustment, it being found efficient for this purpose to associate yieldable springs with one of the rollers. Heretofore, one of the difficulties associated with the maintenance of the rollers in a definite and fixed relationship has been a forced deflection of the rollers which would not permit building machines in sizes greater than where the moment of deflection became a factor that could not be overcome.

A further feature of the invention is the arrangement of the first-fold rollers and the roller that receives the folded sheet from the looper with their axes arranged at an acute angle. The arrangement of the axes of these three rollers at an acute angle is found to be preferable for the reason that the sheet as it comes from the looper traverses a shorter distance before it passes under the control of said third roller. Further, when the deflector mechanism is preventing the sheet from entering the looper, the course of the deflection from the first-fold rollers to said third-fold roller is less abrupt, and the sheet passes more quickly from the bite of the first-fold rollers to the bite of the third-folding roller and with greater folder efficiency. This is particularly desirable because, after leaving the bite of the third-folding roller, the operation of perforation takes place, and, as this is an operation requiring the greatest of accuracy, the better the conditions of control between the bites of the first pair of folding rollers and the third-folding roller, the more accurately the perforator will perform its function.

A further object of the invention is the provision of a perforator that is readily accessible to the operator and that can be readily adjusted lengthwise of the roller with which it is associated. Heretofore, the perforator has been arranged to cooperate with the under surface of the roller with which it is associated, and the matter of replacing the perforator blades and of adjusting the perforator transversely of the machine has required considerable labor and loss of time. By positioning the perforator above its associated roller and easily accessible, these disadvantages are avoided. Heretofore, the perfora-

rator has been associated with the under surface of one of the first-fold rollers, the score line has been of uncertain character, and portions of the sheet have been projected through in the form of rough irregular projections, so that, when the sheet passed under the second-fold knife, the side with these projections was engaged by the knife. The fold thus made lacked sharpness and clear definition. In view of the fact that the subsequent folding of the sheet is affected by the accuracy with which the second fold along the score line is effected, the importance of this second fold being made in a sharp and accurate manner is at once manifest. By the present construction in which the perforator is arranged above its associated roller, the perforation is made downwardly instead of upwardly so that the sheet is fed under the second-fold knife with the projections on the under side of the sheet and away from the knife, and the knife accordingly engages a smooth uniform surface with improved folding results.

The invention will be better understood by reference to the accompanying drawings illustrating one embodiment of the inventive idea, and wherein —

Fig. 1 is a perspective view illustrating the improved folder;

Fig. 2 is a plan view of the same;

Fig. 2^a is a detail of certain adjusting mechanisms for timing the cam shaft dependent upon whether the loop mechanism is to be used or not;

Fig. 3 is a transverse sectional view showing the loop mechanism in elevation in association with the first-fold mechanism of the jobber;

Fig. 4 is a detail showing the loop mechanism in its inoperative position;

Fig. 5 is a perspective view of the looper device and its associated mechanism;

Fig. 6 is a detail perspective of adjusting means when small sheets are to be folded;

Fig. 7 is an enlarged detail showing the means that control the position of the deflectors that prevent the entry of the signature into the loop fold mechanism;

Fig. 8 is a detail perspective showing the means for manually operating the deflectors;

Fig. 9 is a diagrammatic view indicating the progress of a sheet from the pile through the first-fold mechanism, the loop fold mechanism, and succeeding right angle fold mechanisms; and

Fig. 10 is a detail of the grid construction.

Referring to the drawings, wherein like reference numerals indicate like parts, 20 indicates a pile of sheets from which the sheets are successively fed to a folding mechanism comprising essentially a blade 21 and rollers 22 and 23. The sheet is folded by the blade 21 and the folded edge of the same passes between the rollers 22 and 23 and into the loop fold mechanism 24 to the position indicated 130

at "2nd" of Fig. 9. It is noted at this point that by the use of a knife at the first-fold the sheet is folded in one-half the time that would be required if the first-fold were made by a 5 loop folder; because with the loop folder the entire sheet is fed into the folding rollers and folded at the surface speed of the rollers, whereas with the knife fold the sheet is positioned under the blade at tape speed (which 10 is greater than the surface speed of the folding rollers) and when the knife introduces it into the folding rollers, the sheet being folded on itself at a center line, the linear extent of the sheet engaged by the folding rollers is only half of that in the looper.

When the folded edge of the sheet engages stops 25, the signature is buckled or looped adjacent the rollers 22 and 23, a second fold is at once made as the result of this buckling 20 or looping, this fold passing between the roller 23 and a roller 26. This position of the signature is illustrated at "3rd" in Fig. 9. The movement of the signature is indicated by the arrows. After the signature has 25 passed between the rollers 23 and 26, it has received two parallel folds. The first right-angle fold is secured by blade 27 forcing the signatures between rollers 28 and 29 at the "4th" position. After the signature has 30 passed between the rollers 28 and 29, it is a 16 page catalogue fold signature and may be delivered at this point. However, it may be subject to other folds if desired, and a further right-angle fold may be secured through 35 means of the blade 30 forcing the signature between the rollers 31 and 32 at "5th." The signature may be delivered at this "5th" position if desired as a 32 page folded signature or it may be subject to another right-angle 40 fold by blade 33 and rollers 34 and 35 at "6th"; or instead of receiving the right-angle fold at the "6th" position it may receive a further parallel fold at the "7th" position through means of the blade 36 and rollers 37 45 and 38. Other folds could be made by other folding means.

This general description of the progress of the signatures will indicate to those skilled in the art the great advantages of the 50 proved jobbing folder by which all of the folds heretofore made on the catalogue folder are secured.

The sheets of the pile 20 are carried beneath the knife 21 by any suitable means as 55 by a plurality of tapes of which two are shown in Fig. 1 at 39 and 40. These tapes pass around and are driven from a feed roller 41 which is driven from a shaft 42 by means of gears 43, 44 and 45, the gear 43 being mounted on shaft 42, the gear 45 being mounted on feed roller shaft 41, and the gear 44 being an intermediate idler. The shaft 42 is driven from the motor 46 through any suitable means as a belt 47 passing around pulley 60 48 on the shaft 42.

The shaft 42 carries a pinion 49 adjacent the pulley 48, which pinion 49 meshes with an idler gear 50 mounted on a stub shaft, which gear 50 in turn meshes with a gear 51 mounted on a two-part cam shaft 52, 52^a 70 (Fig. 2). This cam shaft 52, 52^a carries various cams that operate various knives, delivery boxes, side registering mechanisms, drop rollers, slowdowns and various mechanisms forming part of the construction of the 75 standard jobbing folder. The cam that operates the knife 21 for making the first fold is shown at 53 on shaft 52^a, said cam operating through arm 54, shaft 55 and arms 56, which latter carry the knife 21, to raise and 80 lower the latter.

The folding rollers 22 and 23 have their shafts provided with gears 57 and 58, the shaft on which the gear 58 is mounted being indicated at 58'. Carried by this shaft is a 85 gear 59' that meshes with a gear 60' on shaft 61' around which pass the tapes 62', which deliver the sheets from the loop fold mechanism to the third position. The shaft 58' also carries on its end adjacent the gear 58 a bevel gear 60 that meshes with a similar bevel gear 61 mounted on a shaft 62. This shaft 62 carries a gear 63 adjacent the gear 44, and this gear 63 meshes with a gear 64 carried by drive shaft 42. Inasmuch as the gear 58 90 drives the gear 57 through the connections indicated, the roller 23 will rotate in a clockwise direction while roller 22 will rotate in a counter-clockwise direction as shown in Fig. 1.

After the signature has secured its first fold by means of knife 21 and rollers 22 and 23, the folded sheet passes into the loop fold mechanism.

This loop fold mechanism which has been 105 generally indicated by the reference numeral 24 is composed of a plurality of grids, the upper grids being indicated by the reference numeral 65 and the lower grids by the reference numeral 66. The sheet folded once 110 passes between the upper and lower grids. The upper grids are suspended at one end from a shaft 67 that is threaded through openings in the ends of said grids, and on which the grids are secured by set-screws 68. The shaft 67 is carried by a lower shaft 69 115 which passes through the corresponding ends of the lower set of grids 66. The connection between the shafts 67 and 69 is through a pair of screws 70 and 71 (Figs. 2 and 3) by which screws the shaft 67 may be adjusted toward and from the shaft 69. The shaft 69 is mounted on the side frames 72 and 73 of the folder and is secured in place by a pair of screws 74 and 75.

The mounting of the front end of the lower set of grids is shown in Figs. 3 and 7. A shaft 76 on which is mounted the front end of each of the bottom grids is secured to a pair of brackets 77 (one of which is shown 120

in Fig. 7) by means of suitable screws 78. This bracket 77 is secured to the frame of the machine by means of screws 79. A shaft 80 is threaded through the forward ends of the 5 upper series of grids, and this shaft is adjustable with relation to shaft 76 by means of a pair of screws 81, one of which is provided at each end of said shaft, and which screws are screwed into shaft 76.

10 When it is desired to adjust the upper set of grids 65 with respect to the lower set of grids 66, bolt 82 and lock-nut 83 (Fig. 3) are manipulated, as is also the case with respect to bolt 84 and lock-nut 85. The same 15 adjustment is effected on the other side.

Means are provided in association with the upper grid 65 to determine the point at which the loop or fold in the sheet shall be effected, and this means consists generally of the adjustable gauge 86 that is secured to the upper grids in any suitable manner as by thumb screws 87. The grids are provided with lips or flanges around which projects member 88 on the gauge 86, so that the gauge is supported in any desired position. It will be understood that the thumb screw 87 and the member 88 are provided on each end of the gauge.

Projecting downwardly from the gauge 86 are stops 89 (Fig. 5) against which the folded edge of the sheet engages and which thus act to stop the further movement of the sheet into the loop fold mechanism. After the folded edge of the sheet engages the stops 89, the sheet is buckled or looped and the 35 looped sheet passes through the rollers 23 and 26 (Fig. 9) as illustrated at the "3rd" position.

The roller 26 is mounted on a shaft that is provided with a gear 90 (Fig. 1) that meshes 40 with and is driven from gear 58; and inasmuch as the roller 26 will thus be driven in an anti-clockwise direction, whereas the roller 23 is driven in a clockwise direction, the sheet with its two parallel folds will be 45 fed forward toward the knife 27 as shown in Fig. 9.

If it is desired to utilize the machine for job work, that is to say for the making of a plurality of successive right-angle folds, the 50 use of the loop fold mechanism will be discontinued. This is readily effected by means of a deflecting mechanism mounted on a shaft 91 and comprising a series of deflector plates 92 which, when moved to the position indicated in Fig. 4, will prevent the sheet from entering the loop fold mechanism and will cause the same to move between rollers 23 and 26 and in the direction indicated by the arrow. In Fig. 3 the deflector plates are shown in the 60 position which they occupy when the machine is being used as a catalogue folder and when the sheets are to be operated on by the loop fold mechanism. The deflectors are moved from the position illustrated in Fig. 4 to that 65 illustrated in Fig. 3 by means of a hand-wheel

93 (Fig. 8) mounted on a shaft 94 and connected thereto at 95. This shaft is suitably supported in the frame of the machine. The hand-wheel 93 is provided with a pair of slots 96 with either of which engages an arm 97 pivoted at 97', against which bears a spring 98, to hold the shaft 94 and to lock the deflectors in their operative or inoperative position. The deflector plates 92 are guided in their movement to, and supported in the desired 75 position by means of a guide or master plate 102 (Fig. 7) provided with an inclined slot 102' with which engages a pin 101' carried by an arm 101 mounted on shaft 91. This master plate 102 is secured to the bracket 77. 80

It has been found desirable to adjust the roller 26 with respect to cooperating roller 23 in order to compensate for varying thicknesses of paper and the like, and to this end the roller box 105 at each end of the roller 26 is provided with a depending pin 106 that passes loosely through an opening 107 in the frame of the machine at each end of the roller 26. A spring 108 reacts against a washer 109 at one end and against the bracket 77 at its other end. An adjusting nut 109' and lock-nut 109'' are provided on each pin 106, and manipulation of the same moves the roller 26 toward or from the roller 23. In order to steady the movements of the roller 26 toward and from the roller 23, the shaft on which the roller 26 is mounted is supported in arms 110, which latter are pivoted around shaft 61'. 95

It will be understood that, when the folder 100 is used for jobbing work, that is to say when the sheet is prevented from entering into the loop fold mechanism, the several knives, drop rollers, side guides, slowdowns, and all operating parts should and will be in a definite 105 timed relation. When the folder is to be used for catalogue work, that is to say when the sheet is to enter the looper, the timed relation of the parts will be different. The change in timing involves all of the mechanism in connection with the first fold which

includes the drop rollers 112 for feeding the sheets from the pile to the knife 21, the slowdown fingers 113 for slowing down the sheet at the first fold gauge, the side registering 110 mechanism 114 for positioning the sheet sideways at the first-fold gauge, and the operation of the first-fold knife 21. These operations are controlled from cams on the cam shaft 52^a. The cam for the drop roller is indicated at 112^a, the cam for the slowdown is indicated at 113^a, the cam for the side register is indicated at 114^a and the cam for the first-fold knife as heretofore stated is indicated at 53. The drop rollers 112 are mounted on shaft 115 that carries an arm 116, the free end of which is connected to a strap 117 that carries a roller 118 in engagement with cam 112^a. The slowdown fingers 113 are mounted on a shaft 119 that carries an 115 120 125 130

arm 120, the free end of which is connected to a strap 121 that carries a roller 122 in engagement with cam 113^a. The side registering mechanism 114 is operated from cam 114^a

6 through connection 123.

As heretofore stated, the cam shaft of the machine is composed of two parts 52 and 52^a, and the cams just referred to are mounted on the part 52^a. In order to properly time the 10 operation of these cams when the loop fold mechanism is used, an adjusting mechanism is preferably provided between the two parts 52 and 52^a of the cam shaft. This mechanism (Fig. 2^a) comprises a pair of disks 125 and 126, the former being pinned to shaft 52 and the latter to shaft 52^a. The disk 125 is provided with a tapped hole 127 and the disk 126 with an elongated slot 128. Screw 129 passes through the slot 128 and into the 15 tapped hole 127 and acts to secure the disks 125 and 126 in any desired angularly adjusted position with respect to each other. The shaft 52 projects through the disk 125 and into a recess 130 in the disk 126, in order to prevent 20 the disks from getting out of alignment.

When it is desired to adjust the machine to compensate for the presence of the loop fold mechanism, the screw 129 is loosened. The machine is then turned over by hand through 25 means of the hand-wheel 131 or 131^a which operates to rotate the cam shaft 52 through the gears 49, 50 and 51. It will be appreciated that, when the shaft 52 is rotated under these conditions, the cam shaft 52^a and cams 53, 30 112^a, 113^a and 114^a thereon will remain stationary. The shafts 52 and 52^a are then secured in their adjusted position by screw 129 and disks 125 and 126. The subsequent 35 operation of the parts of the machine controlled by said cams will be retarded over what they were previously when the machine was being operated as a jobbing folder. It is to be understood, however, that the machine can be operated to produce jobbing or catalogue 40 work without using this timing mechanism.

If it is desired to do catalogue work on sheets that are too small to be handled by the operation of the usual gauge 86, a plurality 45 of gauge fingers 132 are provided. These fingers are mounted on the gauge 86 in any suitable manner (Fig. 6) as by clipping the same over the gauge 86 by means of an extension 134. The front ends of the gauge fingers 50 132 are provided with upturned faces 135 that act as the stops for the folded edges of the sheet entering the loop fold mechanism.

While, for the purpose of adapting the jobbing folder to the performance of work here- 55 tofore done on the catalogue folder, any suitable form of looper mechanism may be employed, I have found that superior results are obtained by the use of the novel construction of looper herein illustrated and somewhat 60 generally described heretofore. I, however,

desire to point out certain additional features of the construction and operation of the looper mechanism that have not been particularly specified.

As will be more particularly seen in Figs. 70 2, 3 and 5, the grid members 65 and 66 are curved for the purpose herein set forth, and the several grid members 65 and 66 are assembled and mounted and secured on the shafts 67, 69, 76 and 80 in any desired position of relative adjustment. It will be readily understood to those skilled in the art that any number of grid members either of the lower units 66 or of the upper units 65 may be readily assembled, the number of members on the same depending upon the particular work to be performed, and the particular conditions that are encountered. As will appear more clearly in Fig. 2, a number of the lower grid members 66 may be made 80 shorter, as indicated at 66', in order to cut down the amount of frictional surface which the sheet encounters in the looper. It is pointed out in this connection, however, that in the preferred embodiment all of the upper 90 grid members 65 are preferably of a length equal to that of the grid members 66, only the lower members 66' being preferably of shorter extent than the companion lower members 66. The particular construction of 95 the lower grid members 66 or 66' will be better understood by reference to Fig. 10, in which the sheet-engaging surface, at the point where the sheet enters the grid members, is indicated at 66'' with the width of the 100 sheet-engaging surface progressively decreasing rearwardly of the grid member to a point where it is, at 66''', the rib or bottom of an inverted T member. This construction is also clearly shown in Fig. 5. 105 The corresponding surfaces of the upper grid members 65 are preferably likewise progressively decreased in their sheet-engaging surfaces.

The short lower members 66' are mounted 110 on the shaft 76, and the upper and lower members on shaft 67, 69, 76 and 80, and as heretofore stated, the individual and separable deflecting elements 92 are mounted on the shaft 91. It will accordingly be understood 115 that a looper of any desired size and with any desired spacing of the elements, depending upon the conditions encountered and the work to be performed, may be built up readily by threading the grid members 65, 66, 66' 120 and the deflectors 92 on their respective shafts, and thereafter securing the grid members and the deflectors in any desired position of adjustment by the means heretofore described.

The first-fold rollers 22 and 23 are spaced apart, as clearly shown in Figs. 3 and 4 and are yieldingly held in this spaced position, which normally is slightly less than the thickness of the paper passing between said rollers. 130

As shown, particularly in Fig. 8, the roller 22 has associated therewith at each end thereof a coil spring 140, through which passes a pin 141. The spring 140 at one end engages the bearing in which the shaft of the roller 22 is mounted, and at its other end engages a bracket 142 secured to the frame of the machine. On the side of said bracket 142, opposite to that which is engaged by the spring 140, is an adjusting nut 143 and a lock-nut 144 by which the roller 22 is adjusted with great accuracy with relation to roller 23, and is thereafter secured in this adjusted position, so that the rollers 22 and 23 cannot approach each other closer than this position of adjustment, though roller 22 may yield with respect to roller 23 by reason of the presence of spring 140, as will be understood.

Roller 26 is likewise held in spaced relation to roller 23, the spacing being somewhat less than the thickness of the folded sheet which passes between the rollers 23 and 26. A similar adjustment at 109' and 109" insures the limits of the approach of roller 26 to the roller 23, but the spring 108 will permit the roller 26 to yield with respect to the roller 23 when a folded sheet passes between the same.

As will be seen particularly from Figs. 3, 4 and 5, the tapes 62' pass around the roller 61', which roller, in the preferred embodiment as herein shown, has its axis in substantially the same horizontal plane that passes through the axis of the roller 26. Accordingly, the tapes 62' can be readily adjusted. This roller 61' is provided with a plurality of slots 133 with which the perforator 134 cooperates. This perforator is of the usual construction, being provided with a series of removable blades 135, and said perforator is mounted on a shaft 136 arranged above said roller 61'. It is accordingly readily accessible and easily adjustable axially in order that the blades 135 may engage with any one of the slots 133, and in order that the blades 135 may be readily removed and replaced, the slots 133 cleaned out, and principally in order that the rough irregular projections may be on the under side of the sheet away from the second folding knife.

It will be understood that the invention, with respect to the first feature under discussion, relates particularly to the control of the first two folds of the sheet which determines whether catalogue or jobbing work is to be done by using either the loop fold mechanism for making the first two folds parallel or by disconnecting the loop fold mechanism so that the first two folds are right-angle folds; and it will accordingly be unnecessary to further describe the folding operations on the signature.

While, for the purpose of illustration, one

expression of the inventive idea has been illustrated and described in detail, it is to be understood that the invention is not limited thereto, but that the inventive concept is susceptible of various mechanical expressions within the limits of the appended claims, the invention in the first aspect discussed having utility on all knife folders on which the first two folds are required to be parallel followed by another fold or folds; and the novel construction of looper mechanism, the arrangement of the folding rollers, the perforator, etc., having a broad range of usefulness in various machines.

What is claimed is:

1. In combination, a reciprocating folding blade, means for feeding and positioning successive sheets under said blade, a looper attachment positioned adjacent said first-fold mechanism and receiving the signature therefrom and forming a second parallel fold therein, means for preventing the folded sheet from being operated on by said looper mechanism, and a third folding mechanism receiving the sheet from said looper mechanism and giving the same a third fold.

2. In a folder, the combination of a plurality of right angle folding mechanisms employing reciprocating knives and a loop folding device receiving the folded sheet from the first folding mechanism whereby the first two folds are parallel to each other.

3. In a folder, a plurality of right angle knife folder mechanisms, the combination of a looper attachment positioned adjacent the first knife folder and receiving the signature therefrom, and means controlling said looper attachment whereby the product is folded with folds at right angles to each other or with the first two folds parallel.

4. In a folder, the combination of a first fold reciprocating knife and a pair of folding rollers, a third roller associated with one of said rollers, a grid positioned adjacent said third roller to loop the sheet to effect a parallel fold, and a second knife folder mechanism receiving said signature from said looper mechanism and making a fold at right angles to said parallel folds.

5. In a folder, the combination of a first fold reciprocating knife and a pair of folding rollers, a third roller associated with one of said rollers, a grid positioned adjacent said third roller to loop the sheet to effect a parallel fold, and a second knife folder mechanism receiving said signature from said looper mechanism, making a fold at right angles to said parallel folds, and a deflector for preventing the sheet from entering the grid.

6. In a folder, the combination of knife and loop fold mechanisms for performing jobbing and catalogue work comprising a knife folder, a looper mechanism associated therewith for making a parallel fold, a knife folder arranged at right angles to the looper

mechanism and receiving the signature therefrom, and means for rendering said looper mechanism inoperative.

7. In a folder, the combination of knife and loop fold mechanisms for performing jobbing and catalogue work comprising a knife folder, a looper mechanism associated therewith for making a parallel fold, a knife folder arranged at right angles to the looper mechanism and receiving the signature therefrom, and a deflector for rendering said looper mechanism inoperative.

8. In a folder, the combination of knife and loop fold mechanisms for performing jobbing and catalogue work comprising a knife folder, a looper mechanism associated therewith for making a parallel fold, and a knife folder arranged at right angles to the looper mechanism and receiving the signature therefrom.

9. In a folder, the combination of a first fold reciprocating knife and a pair of folding rollers, a third roller associated with one of said rollers, a grid positioned adjacent said third roller to loop the sheet to effect a parallel fold, and a second knife folder mechanism receiving said signature from said looper mechanism.

10. In a folder, the combination of knife and loop fold mechanisms for performing jobbing and catalogue work comprising a knife folder, a looper mechanism associated therewith for making a parallel fold, a knife folder arranged at right angles to the looper mechanism and receiving the signature therefrom, means for rendering said looper mechanism inoperative, and means for changing the timing relation of the parts dependent upon whether jobbing or catalogue work is being performed.

11. In a folder, the combination of knife and loop fold mechanisms for performing jobbing and catalogue work comprising a knife folder, a looper mechanism associated therewith for making a parallel fold, a knife folder arranged at right angles to the looper mechanism and receiving the signature therefrom, means for rendering said looper mechanism inoperative, and means for changing the timing of the devices associated with the first fold mechanism when catalogue work is being performed.

12. In a folder, the combination of knife and loop fold mechanisms for performing jobbing and catalogue work comprising a knife folder, a looper mechanism associated therewith for making a parallel fold, a knife folder arranged at right angles to the looper mechanism and receiving the signature therefrom, means for rendering said looper mechanism inoperative, a two-part cam shaft, and means for angularly adjusting one part with respect to the other.

13. In a folder, the combination of knife and loop fold mechanisms for performing

jobbing and catalogue work comprising a knife folder, a looper mechanism associated therewith for making a parallel fold, a knife folder arranged at right angles to the looper mechanism and receiving the signature therefrom, a plurality of deflecting members for rendering said looper mechanism inoperative, and a master member controlling the movement of said other deflecting members.

14. In a folding machine, a looper mechanism comprising two grid members each composed of a plurality of separate independent grid elements, and means for adjusting said elements with respect to each other.

15. In a folding machine, a looper mechanism comprising two grid members each composed of a plurality of separate independent curved grid elements, and means for adjusting said elements with respect to each other.

16. In a folding machine, a looper mechanism comprising grid elements the contact surface of which decreases from the point where the sheet enters the looper mechanism.

17. In a folding machine, a looper mechanism composed of a plurality of separable and removable curved grid elements the surface of which grid elements that is engaged by the sheet progressively decreasing from the point where the sheet enters the looper mechanism.

18. In a folding machine, a looper mechanism having lower curved grid members of different lengths and an upper grid member similarly curved.

19. In a folding machine, a looper mechanism composed of a plurality of separable curved lower grid members, and a plurality of separable curved upper grid members.

20. In a folding machine, a looper mechanism having a grid member of substantial sheet-engaging area at the point where the sheet enters the looper and diminishing to a substantial smaller sheet-engaging surface.

21. In a folding machine, a looper mechanism composed of a plurality of lower curved grid elements, a plurality of upper curved grid elements, and a plurality of individual deflector elements spaced between each pair of upper and lower grid elements.

22. In a folding machine, a looper mechanism made up of a plurality of separable grid elements and a plurality of removable deflector elements, and means for adjusting the deflector elements into operative or inoperative position while in situ.

23. In a folding machine, a looper mechanism made up of a plurality of separable grid elements and a plurality of removable deflector elements, means for adjusting the deflector elements into operative or inoperative position while in situ, and means for locking said deflector elements either in or out of operative position.

24. In a folding machine, a looper mechanism provided with a grid, a plurality of

- deflector elements associated with said grid, and a master member for controlling the positioning of said deflector elements.
25. In a folding machine, the combination of a looper mechanism, a plurality of deflector elements associated therewith, a shaft on which said deflector elements are mounted, an arm secured to said shaft, and an operating connection controlling the movement of said 10 arm.
26. In a folding machine, the combination of a pair of first-fold rollers mounted out of contact with each other and spaced apart a distance less than the thickness of the sheet 15 passing therebetween, and a third-fold roller mounted below and with its axis arranged in a vertical plane passing substantially through the axis of one of said first-fold rollers, said third-fold roller and its associated first-fold 20 roller being mounted out of contact with each other and at a distance slightly less than the thickness of the folded sheet passing therebetween, and means for permitting the separation of the rollers as the sheet passes there- 25 between, the axes of the first-fold rollers and said third-fold roller being arranged at an acute angle.
27. In a folding machine, the combination of a set of first-fold rollers, a third roller associated with and arranged below one of said first-fold rollers, a perforator and a roll 30 cooperating therewith, and means feeding the folded sheet from said third roller to said perforator, said perforator being arranged above its associated roller.
28. In a folder, the combination of a first fold reciprocating knife and a pair of folding rollers, a third roller associated with one of said rollers, and a grid positioned adjacent 35 said third roller to loop the sheet to effect a parallel fold.
29. In a folding machine, the combination of a first fold knife, a pair of folding rollers associated therewith, a third roller associated with one of said knife folding rollers through which the sheet is looped, a fourth roller independent of said folding and looping rollers, a succeeding folding mechanism, and tapes passing around said fourth roller and carrying the folded sheet to said succeed- 45 ing folding mechanism.

In testimony whereof I have signed this specification.

EARL D. RADER.
